UNITED STATES PATENT OFFICE.

ISAAC H. MILLIKEN, OF ASPINWALL, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT-YOKE.

1,309,297.

Specification of Letters Patent.

Patented July 8, 1919.

Application filed July 31, 1917. Serial No. 183,752.

To all whom it may concern:

Be it known that I, ISAAC H. MILLIKEN, a citizen of the United States, residing at Aspinwall, in the county of Allegheny and State of Pennsylvania, have invented certain new and useful Improvements in Draft-Yokes; and I do hereby declare the following to be a full, clear, and exact description of the invention, such as will enable others skilled in the art to which it appertains to make and use the same.

My invention relates to the construction of draft yokes forming an element of railway draft rigging. The object of the invention is to produce a simple form of draft yoke which is strong, reliable and efficient in service, which may be readily manufactured, and in which casting strains or similar defects are unlikely to occur. Generally stated, this object is accomplished by forming the yoke with spaced arms which are connected near their forward ends by a transversely extending upright member having on its forward face a curved segmental bearing surface that is adapted to coöperate with the correspondingly curved butt of a car coupler (not shown), a pair of parallel side walls which are spaced laterally from the curved bearing and extend forwardly from the upright member being also employed to connect the forward portions of the yoke arms. Such a construction embodies the principal features of the invention.

In the drawings illustrating the best mode in which I contemplate applying the principle of my invention, the scope whereof is pointed out in the claims.

Figure 1 is a plan view of a draft yoke embodying the invention.

Fig. 2 is a view, partly in vertical longitudinal section and partly in side elevation, of the construction illustrated in Fig. 1.

Fig. 3 is a section on the line 3—3, Fig. 2.

Fig. 4 is a plan view of another form of draft yoke embodying the invention.

Fig. 5 is a side elevation of the construction shown in Fig. 4.

Fig. 6 is a sectional view, taken on the line 6—6, Fig. 5.

In the construction illustrated in Figs. 1, 2 and 3 of the drawings, 1, 1 are the yoke arms between which the well known arrangement of springs and followers or other cushioning unit (not shown) may be interposed. Near their forward ends the yoke

arms 1 are united by an upright transversely extending member 2 the rear face 3 of which is adapted to engage the forward follower of the draft rigging in the customary manner. The upright member 2 is provided at the center of its forward face with a curved segmental bearing surface with which the butt of a car coupler (not shown) may engage. In the special form of construction shown in the drawings this segmental bearing is separated into two parts 4, 4 by a lug 5 which projects forwardly from the upright member 2. The lug 5 is provided with a perforation 6 adapted to receive a pivot pin (not shown) by which the coupler and yoke may be connected, and it is preferably fashioned at its outer end with a plurality of curved flanges 7 which border its upper and lower edges.

Extending forwardly from the transversely extending member 2 are a pair of side walls 8 which respectively connect adjacent portions of the yoke arms 1. These side walls, which are preferably parallel, are spaced outwardly from the curved segmental bearing surface 4 so as to allow the coupler to swing laterally. When the rear face 3 of the upright member 2 is flat from side to side of the yoke, the space between each side wall 8 and the adjacent end of curved bearing 4 is preferably recessed or hollowed out, as indicated at 9, thus decreasing the mass of metal at this point. The forward ends of the yoke arms 1 are rounded and provided with perforations 10 to form lugs 11 which, like the centrally disposed lug 5, are adapted to receive the tail pin for pivotally attaching a car coupler to the draft yoke.

Except as hereinafter pointed out, the construction illustrated in Figs. 4, 5 and 6 does not differ from that shown in Figs. 1, 2 and 3 and heretofore described. It will, therefore, be unnecessary to describe this modification of the invention in detail. In this form of the invention the transversely extending upright member 2^a which connects the yoke arms 1^a has a rear face that is provided with a centrally disposed follower engaging surface 3^a and a plurality of laterally disposed follower engaging surfaces 3^b, said follower engaging surfaces being separated by intervening depressions 3^c. The ends of the centrally disposed curved segmental bearing surface 4^a on the forward

side of the upright member 2^a are spaced inwardly from the side walls 8^a connecting the outer ends of the yoke arms, the forward surfaces of the yoke which intervene between these parts being, as shown at 9^a, preferably flat. The middle lug 5^a and the outer lugs 11^a of this form of my draft yoke are preferably respectively identical with the lugs 5 and 11 of the construction shown in 10 Figs. 1, 2 and 3.

I claim:

1. A draft yoke for railway draft rigging, comprising a pair of spaced arms, a transversely extending member connecting said 15 arms adjacent the forward portions thereof, and a pair of side walls connected to and extending forwardly from said transversely extending member, said walls also being connected to the adjacent portions of the 20 said yoke arms, and the said transversely extending member being provided on its forward face with a curved segmental bearing surface spaced from the said side walls to reduce the mass of metal at the junctions 25 of said transversely extending member and side walls.

2. A draft yoke for railway draft rigging,

comprising a pair of spaced arms, an upright member connecting the said arms adjacent the forward ends thereof, said member being provided on its forward face with a plurality of curved bearing surfaces separated by a forwardly extending lug, a pair of parallel side walls extending forwardly from the said upright member and 30 connected to the adjacent portions of the yoke arms, the said bearing surfaces being spaced from the said side walls to reduce the mass of metal at the junctions of said upright member and said side walls. 40

3. A draft yoke for railway draft rigging, comprising a pair of spaced arms, and an upright transversely extending member uniting said arms adjacent the forward ends thereof, said upright member having on its 45 forward face a curved bearing surface and having upon its rear face a centrally disposed follower engaging surface interposed between a plurality of laterally disposed follower engaging surfaces, and having intervening depressions between said follower engaging surfaces. 50

In testimony whereof I affix my signature.

ISAAC H. MILLIKEN.
